Inventor
By his Attorney Chas. C. Tillman

UNITED STATES PATENT OFFICE.

JOSEPH T. SOLOMON, OF CHICAGO, ILLINOIS.

COPY-HOLDER.

SPECIFICATION forming part of Letters Patent No. 430,894, dated June 24, 1890.

Application filed May 3, 1890. Serial No. 350,485. (No model.)

To all whom it may concern:

Be it known that I, JOSEPH T. SOLOMON, professor, a citizen of the United States, residing at Chicago, in the county of Cook and 5 State of Illinois, have invented a certain new and useful Improvement in Copy-Holders, of which the following is a specification.

My invention relates to improvements in copy-holders; and it consists in certain 10 peculiarities of the construction and arrangement of the different parts of the same, as will be hereinafter more fully set forth, and specifically claimed.

The object of my invention is to provide a 15 copy-holder which will be simple in construction and operation, inexpensive, durable, and attractive in appearance, and effectual in its working, both as a copy-holder and line-indicator; and it will be found useful to com- 20 positors, copyists, operators of type-writing machines, and all persons having copying or similar work to perform.

In order to enable others skilled in the art 25 to which my invention pertains to make and use the same, I will now proceed to describe it, referring to the accompanying drawings, in which—

Figure 1 is a perspective view of my copy- 30 holder, showing the copy in position. Fig. 2 is a side view of the same, and Fig. 3 is a view of the back of the holder.

Similar letters refer to like parts throughout the different views of the drawings.

A represents a flat plate made of suitable size 35 and material, but usually of japanned tin or sheet metal, and is formed at its lower end with a cylinder or tube a, which extends horizontally across the lower end of the plate and projects slightly to either side thereof, as at 40 b b, these projecting ends being provided with a serrated or milled rubber ring a' to prevent the device slipping when placed upon a smooth surface. The upper end of the plate A is bent back upon itself at its rear and is 45 formed with a tube c for the reception and retention of a wire rod d, which is bent near each end, so as to form a hook d', and at its center a long arm c', which arm may be covered with a suitable casing c² to strengthen 50 the arm and to render it less flexible, and may also be provided with a rubber collar or

ring c³, similar to those on the projections b b, and for a like purpose.

It will be seen by reference to Fig. 3 of the drawings that the tube c is cut away or formed 55 with openings at proper points to allow the hooks d' and arm c' to project, and that the wire d, being loosely held in the tube, will permit the wire to revolve and to adjust the supporting-arm c' at any desired angle. On 60 each side of the plate A, at the upper portion thereof, is formed a tube e, which extends downwardly a suitable distance on the front surface of the plate, and through which a wire B is passed and retained. On each side of 65 the lower portion of the plate and on the front surface thereof is formed a short tube e', which receives the lower end of the wire B, which is formed so as to extend from the top through the tubes e and e' and to reach across 70 the top of the plate A and to project a little distance therefrom to the rear, as shown in Fig. 2.

C is a removable plate formed with its lower portion turned over, so as to form a tube f on 75 its front surface, and having its sides deflect- ed at substantially right angles and formed with a tube g of sufficient length to fit between the lower end of the tubes e and the upper end of tubes e'. Just above the top of 80 the plate C, and to the front surface of the plate A, is journaled in suitable bearings i a rod D, which projects slightly beyond the sides of the plate A, and is provided at each end with a milled thumb-piece E for turning 85 the rod when desired.

On the rod D at suitable points is placed a number of rubber collars F, which rest lightly upon the face of the plate A until the paper G, upon which the matter to be copied is, is 90 inserted, when they rest upon it and by reason of their elasticity take hold of the same and force it through the aperture between the strip H and the surface of the plate A, the strip H being secured at each end to the plate 95 A, as shown, and slightly raised from the surface thereof to admit of the free passage of the paper. This strip not only retains the paper in position, but also forms a guide for the eye in copying, the line to be copied being just above the upper edge of the strip. 100

It will be understood that by inserting the

ends of the wire B into the tubes e, g, and e' the plate C will be held in place and may be easily withdrawn by withdrawing the ends of the wire B from the tubes e', when the plate 5 C may be slipped off. The upper portion of the wire B, which extends across the top of the plate A at the rear thereof, serves to hold the paper in position and prevents it falling in front when a long sheet of paper is used. 10 As shown in Fig. 1, the plate C is slightly raised, by reason of its deflected sides, above the surface of the plate A, which allows the paper to pass freely between the two plates and protects the eyes from the glare produced 15 by the white paper. I may some times divide the plate C vertically at the center, as shown by dotted lines, in which case the wire B, passing through the tubes e, g, and e', forms a pintle upon which the two portions 20 of the plate are hinged, and may be turned when it is desired to open the doors, so as to place the sheet of paper under the strip H. It is obvious that I may dispense with the plate C, but I prefer to use it for the protection 25 of the eyes, and also when it is desired to copy from a book, the lower portion of which will rest on the tube f, as is apparent. The hooks d' are to be used when it is desired to hang the holder on a compositor's case or 30 other suitable place, and the arm c' to support the holder at any desired incline upon a desk or table.

Having thus fully described my invention, what I claim as new, and desire to secure by Letters Patent, is—

35

1. In a copy-holder, the combination of the plate A, having the tube a, with the projecting ends b b and collars a' thereon, the tubes e e' at the sides of the plate, and the top bent back upon itself and formed with the tube c, 40 with the wire B, having its ends inserted in the tubes e, the wire d, having the hooks d' and arm c', the rod D, having the thumb-pieces E and rubber rollers F mounted thereon, and the strip H, all constructed, arranged, 45 and operating substantially as set forth.

2. In a copy-holder, the combination of the plate A, having the tube a, with the projecting ends b b and collars a', the tubes e e' at the sides of the plate, and the top bent back 50 upon itself and formed with the tube c, with the wire B inserted in the tubes e e', the wire d, having the hooks d', and arm c', having the collar c³ and casing c², the rod D, having the thumb-pieces E and rubber rollers F mounted 55 thereon, the strip H, the plate C, having the tube f, and its sides deflected and formed with the tubes g, substantially as and for the purpose set forth.

JOSEPH T. SOLOMON.
